UNITED STATES PATENT OFFICE.

VINCENT H. FRANCIS, OF DRUMRIGHT, OKLAHOMA, ASSIGNOR TO FRICK-REID SUPPLY COMPANY, OF PITTSBURGH, PENNSYLVANIA, A CORPORATION OF PENNSYLVANIA.

PUMP.

1,284,642.

Specification of Letters Patent. Patented Nov. 12, 1918.

Application filed June 23, 1917. Serial No. 176,557.

To all whom it may concern:

Be it known that I, VINCENT H. FRANCIS, a citizen of the United States, and resident of Drumright, in the county of Creek and State of Oklahoma, have invented a new and useful Improvement in Pumps; and I do hereby declare the following to be a full, clear, and exact description thereof.

My invention relates to pumps for oil or like wells, and has particular reference to a type of pump such as described in my application for Letters Patent, Serial No. 176,556, filed of even date herewith.

In the present invention I provide a double-acting pump of the same general character in which the pumped supply of fluid to the chamber above the piston is not dependent on suction of the piston on its downward movement, the arrangement of the structure permitting more rapid operation which gives the invention special advantage for use in pumping slow-flowing wells.

In the accompanying drawing, Figure 1 is a longitudinal sectional view of my improved pump; and Fig. 2 is an enlarged longitudinal sectional view of one of the check-valves employed.

My improved pump comprises the working-barrel or pumping-cylinder 3 having at its lower end an anchor tube and strainer 4, and having at its upper end the stuffing-box 5.

The pump is connected to the well-tubing (not shown) preferably by a tubelike member 6 which is coupled to the well-tubing and connects to the working-barrel by a coupling 7, said coupling forming also a seat for supporting the stuffing-box. The working-barrel has the standing valve 8 and the traveling valve or piston 9. The valve and the piston being preferably of standard form and arranged to function in a manner common to ordinary pumping outfits, the piston in this instance being connected to the operating cable or rods (not shown) by a valve-rod 10 which passes through the stuffing-box 5.

Admission of fluid to the working-barrel beneath the piston is by valve 8 and by a by-pass pipe connection 11. This by-pass connects with the anchor tube below the strainer openings at 11^a and to the working-barrel above the valve 8 at 11^b, a downwardly-seating check 12 preventing return flow of fluid through this pipe. This ar-

angement of the by-pass affords additional means for supplying fluid to the chamber when fluid in the well does not cover the strainer openings; the point of connection of the by-pass to the anchor tube is well toward the bottom of said tube and provides for supply of the fluid to the chamber so long as there is fluid in the well.

The fluid escape openings from the chamber beneath the piston comprise the valve opening of piston-valve 9^a, and the inlet opening 11^b of the by-pass 11.

An extension 11^c of the by-pass 11 communicates with the opening 11^b in the barrel and with the connecting member 6 of the well-tubing and has the downwardly-seating check-valve 13 which opens on the downward movement of the piston.

Chamber 3^a communicates by a by-pass pipe 14 with the source of fluid supply, and an extension 14^a of this pipe connects the chamber with the well-tubing, check-valves 15 and 16 controlling flow of fluid through these pipes, respectively.

The operation of the pump is as follows: Downward movement of the piston forces fluid from the barrel beneath the piston through the opening 11^b into the by-pass pipe 11^c, valve 12 of the by-pass 11 closing due to the pressure of fluid created by the descending piston, the fluid passing through pipe 11^c into the extension 6 which communicates with the well-tubing. During the downward movement of the piston a portion of the fluid beneath the piston passes through the valve 9^a and into the chamber 3^a of the working-barrel above the piston, and in this manner the piston is relieved of compression to a considerable extent on its downward stroke, while at the same time the valve 9^a provides means for supplying the chamber 3^a with fluid for displacement by the piston on its upward movement.

The function of the by-pass 14, is to supply fluid to chamber 3^a for pumping displacement by the upstroke of the piston when the head pressure of the well is such as to cause the fluid to rise or stand in this pipe so as to communicate with the chamber through its opening 14^b.

Upward movement of the piston displaces the fluid from the chamber 3^a through opening 14^b and forces it through the extension 14^a into the connection 6, the check-valve 15 of the pipe 14 closing due to the fluid pres-

sure in the pipe 14 caused by the ascending piston, check-valve 16 preventing return of fluid to the chamber at the completion of the upstroke.

5. With the structure here shown and described, it will be seen that I have provided a double acting pump having a single piston in which fluid from the source is conveyed to the barrel at opposite sides of the 10 piston by passages which are independent of the admission valve 8, which provide for large capacity in pumping a fast flowing well, and which provide for a supply of fluid to the barrel for pumping displacement by 15 the piston in either direction of its movement even when fluid in the well is too shallow to be effected by suction of the piston through the standing valve 8.

What I claim is:

20. 1. A pump for oil or other deep wells comprising a pump cylinder, a single piston in the cylinder for suction and for expulsion of fluid to and therefrom, respectively, a plurality of inlets each having separate 25 source of communication with the source of fluid supply and communicating with the cylinder at opposite sides of the piston, a plurality of outlets, and means for transferring a portion of the fluid of the cylinder 30 at one side of the piston to the opposite side for displacement from the cylinder by movement of the piston.

2. A pump for oil or other deep wells comprising a pump cylinder, a single piston 35 in the cylinder for suction and for expulsion of fluid to and therefrom, respectively, a plurality of inlets each having separate source of communication with the source of fluid supply and communicating with the 40 cylinder at opposite sides of the piston, a plurality of outlets, and a passage for fluid interiorly of the cylinder forming communication between said inlets from opposite sides of the piston.

45. 3. A pump for oil or other deep wells comprising a pumping cylinder, a single piston for simultaneous suction and expulsion of fluid from the cylinder, a plurality of inlets having separate sources of communication with the source of fluid supply, a plurality of outlets, said inlets and outlets being valve-controlled, a valved connection for the fluid of the cylinder communicating at opposite sides of the piston through 50 which a portion of the fluid at one side of the piston is transferred to the opposite side for expulsion from the cylinder by movement of the piston.

55. 4. A pump for oil or other deep wells comprising a pumping cylinder, a single piston for simultaneous suction and expul-

sion of fluid to and from the cylinder, respectively, a plurality of inlets each having separate source of communication with the source of fluid supply for supplying fluid 65 to the cylinder at one side of the piston, said inlets including a valve at one end of the cylinder, a fluid connection communicating with the source of fluid supply at the opposite side of the piston, said inlets 70 being valve-controlled, valve-controlled outlets, and a valve-controlled passage interiorly of the cylinder for conveying fluid in the cylinder from one side of the piston to the opposite side for expulsion from the 75 cylinder by movement of the piston.

5. A pump for oil or other fluids comprising a pumping cylinder closed at one end by a stuffing-box and having a valve-controlled opening in the opposite end, a 80 single piston operable in the cylinder for suction and for expulsion of fluid to and therefrom, respectively, the piston rod of the piston operating through said stuffing-box, a plurality of inlets for the cylinder 85 each having separate source of communication with the source of fluid supply, said inlets including the valve in the end of the cylinder, a plurality of outlet connections, said inlets and said outlets intercommunicating and being valve-controlled, and a communicating passage between the opposite chambers of the cylinder formed by the piston adapted for conveying fluid for expulsion from one of the chambers by movement of the piston. 90

6. A pump for oil or other fluids comprising a pumping cylinder closed at one end by a stuffing-box and having a valve-controlled opposite end, a single piston in the 100 cylinder operated by a piston-rod passing through said stuffing-box, fluid inlets comprising the valve in the cylinder and bypass connections each having separate communication with the source of fluid supply, 105 and communicating with the cylinder at opposite sides of the piston, fluid outlets comprising pipe connections communicating with said inlets, said inlets and outlets being valve controlled operable by movement 110 of the piston, said piston having a passage for conveying fluid from one side of the piston to the other on movement of the piston in one direction for displacement by thrust of the piston in the opposite direction, 115 and a valve controlling said passage.

In testimony whereof I, the said VINCENT H. FRANCIS, have hereunto set my hand.

V. H. FRANCIS.
